(57) **CLAIM**

The ornamental design for a folding chair, as shown and described.

DESCRIPTION

FIG. 1 is a front elevation view of a folding chair showing the new design in a first state;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof; and,

FIG. 8 is a perspective view of the folding chair showing the new design in a second state.

The broken lines shown in the drawings illustrate portions of the article that form no part of the claimed design.

1 Claim, 8 Drawing Sheets
